P. BAUMER

LOOSE LEAF BINDER

Filed May 17, 1927

Inventor:

Paul Baumer,
By atty

UNITED STATES PATENT OFFICE.

PAUL BAUMER, OF FRAUENFELD, SWITZERLAND.

LOOSE-LEAF BINDER.

Application filed May 17, 1927, Serial No. 192,024, and in Switzerland May 22, 1926.

The present invention relates to a loose-leaf binder with which the leaves are held between clamping members or plates and are pushed over holding members by means of unslotted holes and are further provided with slotted perforations for the passage of guide members adapted to be put through one of the clamping members, the guide members being fixed in the other of the clamping members. These guide members serve to hold together the parts of the binder if changes in the number or in the arrangement of the leaves are to be made so that the staple of leaves or a part thereof are solely held in position by the slotted perforations when changes are to be made and when the leaves are pushed on to the guide pins.

According to the present invention the aforementioned guide members are formed by the shanks of a stirrup which are adapted to be inserted into the second clamping member and fixed thereto.

In this manner the tedious screwing and unscrewing of two single pins acting as guide members with the hitherto known types of such binders is avoided so that the handling of the binder when changes have to be made is considerably simplified.

A constructional example of the subject matter of the present invention is illustrated on the accompanying drawings, in which:

Fig. 1 is a vertical section along line I—I in Fig. 2 of the loose-leaf binder.

Fig. 2 is a plan view of the upper clamping member,

Fig. 3 is a plan view of the lower clamping member,

Fig. 4 is an end elevation of the loose-leaf binder and

Fig. 5 is a detail showing some of the perforations of a leaf.

The loose leaves 1 are arranged between two hollow clamping bars or plates 2, 3 provided with the axles of hinge joints by means of which covers 4 are hinged. To screw nipples 5 fixed in the bar 3 two extensible post sections 6 are screwed with each of which two similar sections 6' are connected, which form holding members the length of which can be adjusted in order to permit altering the thickness of the binder. These holding members are provided with a head part 7 screwed to the sections 6', having two annular grooves 7' and 7" arranged

one above the other and with which a locking slide 8, guided inside the hollow bar 2 and normally held in its locking position by means of tension springs 9, cooperates. A tongue 8' provided at one end of the slide 8 and projecting beyond the one end of the hollow bar 2 permits the displacement of the slide against the influence of the springs 9, so that the bar 2 may be disengaged from the grooves of the head parts 7. A lock 10 permits the securing of the slide 8 in its locking position whereupon an undesired removal of the clamping bar 2 from the holding members 6, 6', 7 is rendered impossible. At the side of the bar 2 adjacent to the staple of leaves two plate springs 11 are provided secured at one end to the clamping bar 2 so as to exert an elastic pressure on the stapled leaves. This pressure may be adjusted to be less or greater and in correspondence with the thickness of the staple of leaves by causing the slide 8 to engage with the upper or lower of the annular grooves 7' or 7" respectively of the head parts 7.

The leaves 1 are placed by means of unslotted holes 15 (Fig. 5) over the above-mentioned two holding members 6, 6', 7 and the two shanks 12' of the stirrup 12 pass through slotted perforations 16 of the leaves, the stirrup 12 passes through holes provided in the clamping bar 2 and is loosely connected with the clamping bar 3, i. e. inserted into holes of the latter. In the clamping bar 3 a locking slide 13 is provided adapted to engage annular grooves provided at the ends of the shanks 12' in order to secure the stirrup in position. The slide 13 is normally held in its locking position by means of a tension spring 14 and the slide may be displaced out of its locking position for the purpose of releasing the stirrup 12 by means of an extension 13' at the end of the slide 13.

If, for example, a leaf has to be removed from the staple of leaves the clamping bar 2 is first disengaged from the two holding members 6, 6', 7 by withdrawing the slide 8, whereupon the two clamping bars 2 and 3 which are placed so that their rear edges rest on a support, for instance a table, are moved away from each other. The clamping bar 2 and the loose leaves 1 are thereby guided by the long shanks 12' of the stirrup 12. Enough leaves are removed from the holding members 6, 6', 7 so that the leaf to be ex-

changed is the lowermost of them. As the last-mentioned leaf is now only held in slotted perforations 16 on the horizontally placed shanks 12' of the stirrup it can be easily removed from the staple without being injured. A new leaf is inserted into the book in a similar manner.

If desired the head parts of the holding members may be provided with more than 16 two annular grooves arranged above each other so that a correspondingly larger range in which the upper clamping bar can be adjusted along the holding members is provided, obviously these head parts may also 15 be provided with but a single annular groove.

I claim:

1. A loose-leaf binder, comprising in combination, a lower clamping member, an upper clamping member, extensible holding members fixed in the lower clamping member, means adapted to fix the upper clamping member to said holding members, a stirrup whose shanks pass through the upper 25 clamping member, and means to fix said shanks in the lower clamping member, the leaves to be inserted having unslopped perforations through which said holding members pass and slotted apertures for engaging 30 with said guide members.

2. A loose-leaf binder, comprising in combination, a lower clamping member, an upper clamping member, extensible holding members fixed in the lower clamping member, means adapted to fix the upper clamping member to said holding members, a stirrup whose shanks pass through the upper clamping member, and a locking slide guided in 35 said lower clamping member and adapted to cooperate with notches in said shanks for securing the latter in position, the leaves to be inserted having unslopped perforations through which said holding members pass and slotted apertures for engaging with said 40 guide members.

3. A loose-leaf binder, comprising in combination, a lower clamping member, an upper clamping member, extensible holding members fixed in the lower clamping member and provided with heads, a locking slide guided in said upper clamping member and adapted to engage said heads of said holding members for fixing the upper clamping member to said holding members, a stirrup 50 whose shanks pass through the upper clamping member, and means to fix said shanks in the lower clamping member, the leaves to be inserted having unslopped perforations through which said holding members pass 55 and slotted apertures for engaging with said guide members.

and slotted apertures for engaging with said 60 guide members.

4. A loose-leaf binder, comprising in combination, a lower clamping member, an upper clamping member, extensible holding members fixed in the lower clamping member and provided with heads with a plurality 65 of annular grooves one arranged above the other, a locking slide guided in said upper clamping member and adapted to be selectively brought into engagement with any one of said grooves for fixing the upper clamping member to said holding members, a stirrup whose shanks pass through the upper clamping members, and means to fix 70 said shanks in the lower clamping member, the leaves to be inserted having unslopped perforations through which said holding members pass and slotted apertures for engaging 75 with said guide members.

5. A loose-leaf binder, comprising in combination, a lower clamping member, an upper clamping member provided with spring means at its lower side to engage the uppermost leaf, longitudinally adjustable holding members fixed in the lower clamping member, means adapted to fix the upper clamping member to said holding members, a stirrup whose shanks pass through the upper clamping member, and means to fix said shanks in 80 the lower clamping member, the leaves to be inserted having unslopped perforations through which said holding members pass and slotted apertures for engaging 85 with said guide members.

6. A loose-leaf binder, comprising in combination, a lower clamping member, an upper clamping member, extensible holding members fixed in the lower clamping member and provided with heads with a plurality 90 of annular grooves one arranged above the other, a locking slide guided in said upper clamping member and adapted to be selectively brought into engagement with any one of said grooves for fixing the upper clamping member to said holding members, a stirrup whose shanks pass through the upper clamping member, and means to fix said shanks in 95 the lower clamping member, the leaves to be inserted having unslopped perforations through which said holding members pass and slotted apertures for engaging 100 with said guide members.

In testimony whereof, I have signed my 115 name to this specification.

PAUL BAUMER.
